UNITED STATES PATENT OFFICE.

PATRICK LAWRENCE FANNEN, OF NEW YORK, N. Y.

ADJUSTABLE SOCKET WRENCH.

Application filed December 20, 1920, Serial No. 431,869. Renewed September 1, 1922. Serial No. 585,829.

To all whom it may concern:

Be it known that I, PATRICK LAWRENCE FANNEN, a citizen of the United States, and resident of New York city, in the county of 5 New York and State of New York, have invented certain new and useful Improvements in Adjustable Socket Wrenches, of which the following is a specification.

The object of this invention is to produce 10 a strong and simple adjustable socket wrench for putting on and taking off bolt-nuts and having jaws which are more conveniently positioned on either homed nuts or on nuts to be turned home than has heretofore been 15 the case; and having a form that permits the wrench to be used in endwise application to the nuts. It often happens that nuts are used in close proximity to some structural part which interferes sometimes with 20 the application of a wrench to a nut and often prevents a continuous movement of the nut engaging jaws in the actuation of a wrench for putting on or taking off nuts. This is especially the case in motor car construction wherein wrenches embodying the 25 present invention are particularly useful.

In the accompanying drawings, forming a part hereof and illustrating my invention in the best mode now known to me,

30 Fig. 1 is a side elevation of my new wrench, parts being broken away for greater clearness;

Fig. 2 is a front end view of the wrench and

35 Fig. 3 is a rear end view thereof partially in section at line 3—3 through the operating revoluble shaft shown provided with a handle.

Fig. 4 is a side view of the pintle members in partial telescopic assemblage, these 40 pintle members, in the complete assemblage, holding the pair of the wrench levers in hinged relation one to another;

Fig. 5 is a detailed view, partially in section at line 5—5 of Fig. 4, of an operative 45 assemblage of the pintle members with the revoluble shaft.

Referring to that form of my invention which is shown in the drawings, 1 and 1^a, 50 respectively, indicate each of a pair of wrench levers having flat opposed surfaces 2 between their end portions, and exterior walls which are shown cross-sectionally convex throughout their length. In the completed assemblage, the levers 1 and 1^a are 55 approximately round in cross-section, per-

mitting an often convenient endwise use of the wrench. The lever 1 has between its ends, transversely opposed projecting ears 3—3, the edge walls of which are arced; the 60 other lever 1^a has transversely opposed projecting ears 3^a, the edge walls of which are also arced. The ears 3^a severally have an adjacent, arced bearing surface 3^b on which the arced edges of the ears 3 severally abut; and 65 the ears 3 severally have an adjacent, arced bearing surface 3^c on which the arced edges of the ears 3^a severally abut; and the right hand flat side of each ear 3^a (Fig. 3) bears against an opposed flat side of an ear 3 at 70 3^d. All these abutting and contacting surfaces have a sliding fit one on another.

The ears are formed with transversely aligned pintle openings for reception of a pintle whereby the levers are hinged together. 75 The pintle construction as shown comprises a pintle tube 4, having at one end a flange 5, and a telescopic bifurcated pin 6 having at one end a flange 7, the body of the pin fitting the bore of the pintle tube 4, and, 80 in the completed assemblage, having its end that is entrant in the tube 4 upset at 8 on the flange 5 to hold the pintle forming members 4 and 6 together. The arms of the bifurcated pintle pin shank are indicated by 6^a. 85 The pintle tube has between its ends a round hole 9 for reception of an inner end portion of a revoluble shaft. The crotch portion 10 of the pin is arced and each arm 6^a and the crotch portion 10 are formed with a continuous, 90 inwardly projecting rib 6^b which is arced at the crotch portion 10.

In the assemblage, the inward end portion of a revoluble, operating shaft 11 is entered 95 through the hole 9 in the tube 4, after the tube is inserted through the aligned pintle receiving holes of the lever ears. At its forward end the revoluble shaft 11 has a reduced neck portion 12 which terminates in a terminal flange 12^a, and when the bifurcated pin 6 is inserted in the tube 4 its bifurcated rib 6^b fits slidably in the annular groove formed at the neck 12 of the shaft, the arcuate portion of the rib at the crotch portion 10 bearing on the neck 12, and being 100 between the terminal flange 12^a and the shoulder of the shaft adjacent the neck 12. 105

Thus the two levers with their flat inward opposed surfaces 2, facing one another and spaced apart by the projecting ear construction, are hinged together.

On its inward side, rearwardly of the

pintle and in the direction of the extension of shaft 11, each lever is formed with a transverse, three-walled recess having a forward wall 13 that slants inwardly and forwardly in the general direction of the pintle; a wall 14 shown straight, and a rearward bevelled wall 15 that slants outwardly and rearwardly; whereby the two transverse walls 13 and 15, of each recess, are divergent and have their inner ends spaced apart by the intermediate wall 14, the transverse walls 13, 14 and 15 of one lever being opposed to the corresponding walls of the other lever. The outer end wall of each lever is indicated by 16 and the two walls 16 have their inward ends each spaced apart from the revoluble shaft 11 to form a substantial clearance at 11^a between the opposed transversely inward surfaces of the walls 16 and the shaft 11; so that, forwardly of the pintle, the levers may spread apart to a desired distance without the inward transverse walls of the levers rearward of the pintle coming into contact with the shaft 11, which is revoluble at will either in the clockwise or in the counter-clockwise direction. This shaft is shown with a bent handle forming extension 11^b. The opposed three walled recesses at the rearward ends 30 of the levers form a chamber C for a non-revoluble nut-wedge and a threaded portion of the operating shaft; and the end walls 16 of the levers are severally formed on their inner side with an outwardly extending guide-slot 17, one slot being diametrically opposed to the other, and each extending outwardly, in a transverse direction, and forwardly into communication with the chamber C.

That inward portion of the shaft 11 which passes through the chamber C is threaded at 18 for reception of a nut-wedge 19, having diametrically opposed guide pins 20, which may be passed through the diametrically opposed guide-slots 17, and the ends of which are respectively slidable between the side walls 21 of each slot 17. The free ends of the guide pins 20 are long enough always to overlap the margins of the walls 13, 14 and 15, but are short enough always to provide a substantial clearance at 22 between the end of each guide pin 20 and the opposed laterally outward wall of the chamber C, so that the levers may be moved apart forwardly of the pintle without those lever walls, which are opposed to the free ends of the guide pins, abutting and bearing against the free ends of the guide pins.

Forwardly of the pintle, a leaf spring 23 is fixed at 24 to the inner side of one of the levers, the free end 25 of the spring bearing against the opposed wall of the other lever; and forwardly of this spring, which tends to keep the levers spread apart forwardly 65 of the pintle, the inner sides of the levers

are preferably formed each with a transverse concave serrated surface 26, one opposed to the other, whereby, if desired, the wrench may be used flat-wise for application to a nut. But at their front ends the levers are opposingly formed each with a recess 27 at each side of an inwardly extending lug 28, the end walls of each of which are shown embraced by the laterally spaced apart arms 29 of a swinging, nut-engaging jaw 30 pivotally and rockably secured to the lug 28 by pivot pins 31. The opposed faces of the nut-engaging jaws 30 are severally concaved and serrated at 31; these opposed serrated concavities facing towards an imaginary prolongation of the lengthwise axis of the operating shaft 11. Consequently, in its principal use my new wrench may be used in endwise application to a nut, the pivoted-nut-engaging jaws 30 automatically adjusting themselves with reference to the periphery of the nut and their serrated concave surfaces 31 being then positioned for engagement with nut corners, upon which jaws 30 are tightly impinged by turning the shaft 11 and thereby forcing the forward rounded corners 32 of nut wedge against the forward slanted walls 13 and forcing the jaws 30 towards one another against the resistance of the leaf spring 23. In this movement, the shaft 11 is supposed to be turned in the clockwise direction. But if, for any reason, the wedge nut 19 is in a neutral position near the central portion of the chamber C with its guide-pins passing either the intermediate walls 14 or the rearward walls 15, and it is desired to close the jaws 30 by a counter-clockwise rotation of the shaft 11, then the rearward corner portions 33 of the nut wedge may be impinged against the rearward walls 15 to spread the rearward ends of the levers apart and force the nut-engaging jaws 30 toward one another on a nut.

What I claim is:

1. An adjustable socket wrench comprising, in combination a pair of elongated and opposed levers pivotally connected between their ends, the levers being provided forwardly of their pivotal connection with opposed nut engaging surfaces facing the lengthwise axis of the wrench; and a lever closing mechanism comprising a revoluble shaft extending in the direction of the levers, the pivoted levers being oppositely recessed at their rearward ends to form, between such ends, a chamber for reception of a nut wedge; a nut wedge provided with a guide pin; the wall of the chamber being formed with a guide way for said pin to prevent rotation of the nut wedge, and the chamber being also formed with walls for engagement with the nut wedge during movement of the latter in said chamber; a revoluble shaft having a threaded portion 125

110

115

120

intermeshing with the threaded bore of the nut wedge; and means for journalling the shaft in operative relation to the levers.

2. In a socket wrench, a pair of levers having opposed hinge-forming projecting ears, having arched bearing surfaces and transversely opposed pintle receiving openings; a pintle through said openings; a rearwardly extending operating shaft 10 journalled at one end in the pintle; and a non-revolvle, bodily travelling nut wedge having a threaded connection with the shaft; the levers being formed rearwardly of the pintle with a nut wedge receiving 15 chamber having walls for engagement by the nut wedge in its travel whereby the front ends of the levers may be moved one towards the other.
3. As a new article of manufacture, a wrench comprising a pair of jaw levers 20 each extending lengthwise of and opposedly

to the other; each jaw having between its ends a projecting pivot receiving member, one member being supplementary to the other and in overlapping contact with the 25 other; a pivotal connection for such members; at one side of the pivot and located partially between the jaw levers, an operating shaft the inward end of which has a loose connection with said pivotal connection and the other end of which projects as a handle from between the jaw levers; and, connected with the operating shaft, a thereby actuated jaw closing device located 30 between and in working relation to opposed surfaces of the jaw levers, for closing the jaw end portions at the other side of said pivot.

Signed at New York city, in the county of New York and State of New York, this 40 17th day of December, A. D. 1920.

PATRICK LAWRENCE FANNEN.
